ERNST F. HOFMANN, OF POUGHKEEPSIE, NEW YORK.

Letters Patent No. 60,727, dated January 1, 1867.

IMPROVED WINDOW-LATCH.

The Schedule referred to in these Letters Patent and making part of the same.

TO ALL WHOM IT MAY CONCERN:

Be it known that I, ERNST F. HOFMANN, of Poughkeepsie, Dutchess county, State of New York, have invented a new and improved Window-Latch; and I do hereby declare that the following is a full, clear, and exact description thereof, which will enable others skilled in the art to make and use the same, reference being had to the accompanying drawing, forming part of this specification, in which—

Figure 1 represents a transverse section of this invention.

Figure 2 is a plan or top view of the same.

Figure 3 is a longitudinal section of the same.

Similar letters of reference indicate like parts.

This invention consists in the arrangement of a spring-stop or catch in combination with an ordinary revolving latch in such a manner, that when said latch is closed it is securely locked by the spring-stop, and it cannot be opened or forced back until said stop or catch is depressed or made to release the latch.

A represents a revolving latch which turns on a pivot, *a*, secured in a metal case, *B*, and which, when locked, catches over and under a flanged segmental cam, *c*, in such a manner that when the case containing the latch is secured to the meeting strip of the upper sash, and the flanged cam to the meeting strip of the lower sash, and the latch is turned over and made to lock in the cam, the two sashes are securely fastened, and the window cannot be opened until the latch is turned back. An ordinary latch of this kind is held in position simply by the force of its spring, and it can be forced back from the outside by passing a proper tool or piece of metal up between the two meeting strips, which in most windows do not fit close enough to prevent the entrance of a thin piece of steel or iron. In order to prevent the latch being forced back from the outside, I have added to it a spring-catch or stop, *D*, which consists of a notched piece of metal or other suitable material, supported by a spring, *b*, as shown in fig. 3 of the drawing, or which may be made in any other suitable manner and form. The spring which supports the stop, *D*, is riveted to a separate plate, *e*, or, if desired, said plate may be fastened to or cast solid with the bed-plate of the segmental cam, and the stop is so formed that when the latch is made to lock into the cam, *c*, it drops into the recess of the spring-stop and retains the latch firmly in position. In order to open the latch, it is necessary first to depress the spring-stop, *D*, and the operation of forcing back the latch from the outside is rendered impracticable. A stop, *c*, inserted in the catch, *D*, prevents the spring, *b*, from being overstrained, and the correct operation of the spring-catch is insured. By this simple attachment a latch for windows is obtained which is safe and burglar-proof, and which can only be opened from the outside if the window is smashed.

What I claim as new, and desire to secure by Letters Patent, is—

The stop *c*, in combination with the catch *D*, spring *b*, and latch *A*, constructed and operating substantially as and for the purpose set forth.

ERNST F. HOFMANN.
